PARALLEL RULE

John H. Ball, St. Louis, Mo.

Application April 29, 1937, Serial No. 139,653

1 Claim. (Cl. 33—108)

My invention relates to improvements in parallel rulers.

The main object of my invention is to provide a ruler by means of which accurate parallel lines 5 may be readily drawn by bookkeepers and others.

Another object is to provide a ruler of this kind in which the operating elements are all enclosed except for the thumb wheel which is exposed and may be conveniently engaged by the 10 user's thumb to move the rule blade inward or outward as required.

Another object is to provide a ruler comprising an elongated and flat housing having an elongated slot or recess opening out through its 15 forward edge, a rule blade slidably mounted within the slot and held in place therein by toggle links, a thumb wheel exposed through the rear edge of the housing, and links eccentrically connecting the thumb wheel and toggle links in such 20 manner that rotation of the thumb wheel will operate to move the rule blade straightly into or out of the housing.

With these and other objects in view the invention resides in the novel construction and 25 arrangement of parts as hereinafter fully set forth and claimed, reference being had to the accompanying drawing as showing a preferred embodiment of my invention for purposes of exemplification.

30 In the drawing:

Figure 1 is a perspective view of the ruler.

Figure 2 is a view with the housing cover removed.

35 Figures 3 and 4 are enlarged cross sections along the lines 3—3 and 4—4 respectively in Figure 2.

In carrying out my invention I provide a housing, body or rule back 5 of elongated narrow form of a length equal to the desired length of the 40 finished rule and made of any suitable material such as metal, wood, cardboard, Celluloid or the like. This housing, as it will hereinafter be termed, has a recess or chamber 6 opening at the upper face of the rule and enclosed at the 45 ends 7 and the lower edge 8 by uncut portions of the housing. The recess thus opens only at the upper edge 9 of the housing.

A cover or cover plate 10 of the same shape and size as the housing 5 is secured by screws or 50 rivets 11 over the housing covering the face through which the recess 6 opens and the recess thus takes the form of a narrow and deep slot. An elongated flat rule blade 12 is slidably mounted edgewise down into the recess 6 through its 55 open edge and is of such length and thickness as

to just nicely slide into or out of the recess. Adjacent each end of the rule blade 12 and at aligned points in the closed bottom 8 of the recess steps 13 are cut out and in each pair of steps the ends of similarly turned or disposed toggle levers or links 14 are pivotally connected by small pins 15 so that the levers hold the rule blade in place but by "breaking" at their center pivots, joints or knees 16 allow the blade to move in or out as desired.

The lower edge 8 of the housing has a slot 17 cut through at its center flush with the recess 6 and a thumb wheel 18 is journaled on a screw 19 in this slot 17 so that the wheel extends both into the recess and out below the lower edge of 15 the housing. Draw bars or links 23 are pivoted at their inner ends at 20 to this wheel 18 at an eccentric point on the portion of the wheel within in the recess and at their outer ends these bars are pivotally connected to the center joints 16 of 20 the toggle levers 14. The lower edge of the housing is notched out arcuately at 21 to expose as 25 much of the knurled periphery 22 of the thumb wheel 18 as possible.

In operation with the parts in the position 25 shown the user may draw a line along the exposed edge of the blade 12 and then by turning the thumb wheel 18 in the direction indicated the toggle levers 14 will be operated by the draw bars 23 to draw the blade 12 downwardly or inwardly and another line may be drawn at any spacing from the first. The action of the toggle levers being the same at each end of the blade 12 the lines drawn will be parallel and any number of lines may be so drawn by moving the 30 thumb wheel 18 as may be required. This action may be readily carried out without removing the ruler from the paper. Inasmuch as the toggle links are both turned to the same side as shown in the drawing, the resulting action is that the 35 rule blade is moved straightly in and out of the slot or recess, thereby avoiding any danger of binding of the ends of the blade against the ends of the rule back. An important feature too is the spacing of the drawing edge of the blade 40 12 from the paper by the thickness of the housing 5 below the blade as indicated at 23 in Figure 45 3.

The ruler may of course be made in any length and size and may be graduated in inches or other 50 dimensions if desired.

While I have herein set forth a certain preferred embodiment of my invention it is understood that I may vary from the same in minor structural details so as best to provide a practi- 55

cal device for the purposes intended, not departing from the spirit of the invention and within the scope of the appended claim.

I claim:

- 5 A device of the kind described, comprising a rule back recessed at its upper face and out through the predetermined forward edge, and being closed at bottom, ends and back edge, the latter however having a thumb wheel aperture 10 formed medially therethrough, a cover plate secured over the open upper face of the rule back, thereby providing an elongated covered slot between rule back and cover plate, an elongated

flat rule blade seated edgewise and freely within the said slot, similarly turned toggle links pivotally mounted at their ends transversely within opposite ends of the said slot back of the rule blade, a thumb wheel journaled medially 5 within the slot back of the rule blade, the periphery of the wheel being exposed through the thumb wheel slot of the rule back, and a pair of links pivotally connected at their inner ends to an eccentric point on the thumb wheel, the outer 10 ends of the links being pivotally connected to the center joints of the toggle links.

JOHN H. BALL.
